UNITED STATES PATENT OFFICE

2,450,033

MEANS FOR MAKING JELLY ROLLS OR
THE LIKE

Morris Cohen, Kansas City, Mo., assignor to Interstate Bakeries Corporation, Kansas City, Mo., a corporation of Delaware

Application March 24, 1945, Serial No. 584,545

2 Claims. (Cl. 107—4)

1

This invention relates to means for making jelly rolls or the like for use particularly in commercial bakeries, and the present invention aims to provide an improved and simplified machine for this purpose.

The well known bakery product commonly called a jelly roll may consist of a quantity of batter which is first formed as a flat baked slab of, say, sponge cake, upon the upper surface of which is spread a coating of fruit jelly or the like, the slab being then rolled-up, with the jelly coated surface innermost, to form a roll, the coils of the roll advantageously showing at the ends of the roll to display the jelly content.

Among other objects, the present invention aims to provide mechanical means for the production of such jelly rolls with a minimum of manual handling, while at the same time insuring a more uniform disposition of the jelly upon the cake preliminary to rolling-up, and the production of a more uniform coil or roll in the final product.

These and other objects will be more fully pointed out in the following description, taken together with the accompanying drawings, of an illustrative embodiment of the invention, and in which drawings:

Figure 1 is a side elevational view of a machine constructed in accordance with the present invention, being somewhat schematic and with parts broken away for clearness of description;

Figure 2 is a fragmentary elevational view, similar to Figure 1 but showing an alternative position of a part;

Figure 3 is a plan view of the structure of Figure 1; and

Figure 4 is a fragmentary plan view showing a portion, greatly enlarged, of a part of the machine.

Referring in detail to the illustrative construction shown in the drawings, a support is provided in the form of a mobile table 10 comprising side frames 11 and legs 12 which may be reinforced by longitudinal girders 13, wheels 14 at the lower terminations of the legs serving as mobilizing means.

The two parallel main frame parts 11 running longitudinally of the table serve as supports for a table surface or platform 15 for the upper runs of a plurality of longitudinally aligned conveyors such as, in this instance, the endless belt canvas conveyors 16, 17 and 18. The conveyor belts are entrained on the usual conveyor windlasses of which there may be a pair 19 and 20 for the belt 16 carried by axles 21 and 22 respectively, a pair 23 and 24 for the belt 17 carried by axles 25 and 26

respectively, and a pair 27 and 28 for the belt 18 carried by axles 29 and 30 respectively. The axles may be suitably journaled in the side frames 11 as indicated in the drawings.

As shown and broadly claimed in my co-pending application S. N. 525,556, of Morris Cohen, Gerald A. Jorgenson and George Hasty, filed March 8, 1944, for Coating and rolling apparatus and now Patent Number 2,402,874 dated June 25, 1946, the present machine desirably includes a coating or jelly applying device here indicated generally by the numeral 31 and which may include a hopper 32 suitably attached as at 33 to one of the side frames 11 and offset laterally therefrom. The hopper 32 affords a reservoir for a supply of jelly in the fluid state which travels by gravity through the pipe 34 to the pump 35, which is driven by an electric motor 36. The pump 35 and motor 36 may be carried by the girders 13 of the table below the conveyor belts. Rising from the pump 35 is a delivery pipe 37 on the opposite side from the reservoir 32, that is, the side near the observer in Figure 1, which is bent to clear the side of the table and is then turned horizontally across the conveyor belt as at 38 to bring its discharge end 39 over the longitudinal center line of the conveyor. At the discharge end 39 is suitably secured a transverse spreader nozzle 40 which may have a discharge slot 40a elongated longitudinally of the nozzle or transversely of the machine for emission of the jelly or other coating.

The pump 35 is adapted to force the fluid up through the delivery pipe 37 and to the spreader nozzle 40 under pressure except when the pipe 37 is closed by a valve mechanism 41 located in the part 38 of the pipe and controlled in this instance by a solenoid device 42. When the valve mechanism 41 is closed to prevent discharge of the jelly through the discharge nozzle 40, an overflow pipe 43 is provided communicating with the pump 35 at its lower end and having its upper end 44 bent over and turned down into the hopper 32. A relief valve mechanism 45 is associated with the pump 35 and overflow pipe 43 which opens to permit passage of the fluid from the pump to the overflow pipe when the pressure of the fluid in the pipe 37 by closing of the valve mechanism 41 reaches a predetermined point, the latter being adjustable by a hand control-screw 46.

In accordance with the present invention, means are provided for propelling the conveyor belts 16, 17 and 18 at successively faster speeds and, as here shown, by an electric motor 47

mounted on the girders 13 at the opposite end of the table from the motor 47. On the output shaft 48 of the motor 47 are fixed a pair of sprocket wheels 49 and 50 which are of equal diameter. The sprocket wheel 49 has entrained thereon an endless driving chain 51 which is also entrained on a sprocket 52 which is fixed on the axle 26 of the conveyor belt 17. This axle 26 also carries another sprocket 53 which is smaller than the sprocket 52 and which has entrained thereon the driving chain 54 which is also entrained with a sprocket 55 on the axle 22 of the conveyor belt 16, the sprocket 55 being the same size as sprocket 52. The sprocket 50 on the motor output shaft 48 has entrained thereon an endless chain drive 56 which is also entrained on a sprocket 57 carried by the axle 30 of the conveyor belt 18, the sprocket 57 being the same size as the sprocket 50.

Thus operation of the motor 47 will simultaneously drive all three of the conveyor belts 16, 17 and 18, in the direction of the arrow 57a, the motor output shaft 48 being arranged to rotate in the direction of the arrow 57b. In one preferred instance, the speed of the conveyor belt 16 may be twenty-four feet per minute. By providing the sprocket 49 with fifteen teeth, and the sprocket 52 with twenty teeth, and the sprocket 53 with fifteen teeth, and the sprocket 55 with twenty teeth, the conveyor belt 16 will thus run slower than the motor 47 and slower than the belt 17. By providing the sprocket 52 with twenty teeth, the conveyor belt 17 will run proportionally faster than the belt 16 but slower than the output shaft 48. By providing the sprocket 57 with fifteen teeth, the same number as sprocket 50, the belt 18 will thus run at the same speed as the output motor shaft and proportionally faster than the belt 17.

The conveyor belts are adapted to carry thereon, in the direction of the arrow 57a, a series of articles to be dealt with by the machine such as the slabs of cake 58 disposed initially in any suitable manner on the machine, at the lefthand end thereof in the flat and in contact or abutment one with the other as at 59.

It will be understood that the cake slabs are formed of cake batter which has been suitably prepared in the bakery and thereafter baked before being brought to the present apparatus to be prepared into so-called jelly rolls and the cake slabs are commonly say fifteen inches long, that is transversely of the machine, about twelve inches wide, that is longitudinally of the machine, and about five-eighths of an inch thick, and each slab as presently described is here adapted to make two jelly rolls.

When the slabs 58 are travelling on the belt 16, the motor 47 being in operation, electric wire leads being connected with the terminals 60 of the solenoid coil 61 and also connected into the circuit of the motor 47, as will be readily understood and need not be here further described, the solenoid coil is energized and the usual armature 62 of the solenoid device 42 is raised to open the valve of the valve mechanism 41. Thus as the cake slabs 58 travel on the belt 16 under the transverse spreader nozzle 40, the jelly is discharged therethrough in a continuous film or sheet which is disposed by gravity onto the cake slabs thereunder.

Since, in accordance with the present invention, the cake slabs are in abutment, the jelly may be discharged continuously during operation of the machine. If, however, the motor 47 is shut down,

the solenoid coil 61 will be de-energized thus releasing the armature 62 and allowing the valve of the valve mechanism to close under pressure of the fluid in the pipe 37, and so discontinuing discharge of the jelly through the nozzle 40.

With the machine in operation as described, the cake slabs, after being coated with jelly, pass from the conveyor belt 16 to the conveyor belt 17 where their speed is increased so as to begin to space the cake slabs apart, and they are further spaced apart as they pass onto the last conveyor belt 18. They are now spaced apart so as to be individually dealt with by the rolling-up means indicated generally by the numeral 63 which in this instance is shown in the form of a section of flexible chain belt 63a having one end suspended from a rod 64 which is rotatably mounted at its ends as at 65 in a pair of posts 66 upstanding from the table frames 11 respectively.

The chain belt section 63a extends from the post in the direction of movement of the conveyor belt and tends to drag thereon as at 67 (Fig. 2), thus functioning somewhat as a loosely hung flexible apron. A fragmentary enlarged plan view of a portion of the chain apron 63a illustrating one illustrative formation thereof is shown in Figure 4, and in which the metal ribbons 68 are sinuously formed to be loosely interengaged by similar ribbons 69 flexibly joining the ribbons 68 and bent lockingly thereabout providing a device which is extremely flexible longitudinally of the machine but rigid transversely thereof, and which at the same time has sufficient weight to accomplish the purpose next described.

As shown in Figure 2, one of the cake slabs 58 which is here given the additional designating numeral 58a is shown as moving on the belt 18 just at the point where its forward edge contacts the chain apron 63 and this forward edge is shown turned up as at 70. As the slab 58a continues to move forwardly carried by the belt under the apron 63a the dragging function of the latter on the cake slab continues to roll this up as shown at 58b (Fig. 1) at which stage the jelly roll is almost completely rolled up.

As the jelly roll 58b continues still further under the apron 63a, it passes freely under the free edge of the apron and by this time is completely rolled up, and then it becomes desirable to prevent it from uncoiling. For this latter purpose, the expedients next described are advantageously provided.

Suspended over the belt 18 beyond the rolling-up means 63 is a setting device for the jelly rolls generally indicated by the numeral 71 and here shown in the form of a pressure plate 72 spanning the conveyor 18 and adjustably supported thereover as by a link mechanism comprising a pair of links 73 pivoted as at 74 on the side frames 11 respectively and articulated as at 75 with the pressure plate 72, another pair of links 76 similarly pivoted as at 77 on the frame intersecting the links 73 respectively at 78. A sub-link 79 is articulated as at 80 with each link 76 and as at 81 with the pressure plate. The connection 78 is both pivotally and slidably adjustable to permit raising or lowering of the pressure plate and the adjustment may be fixed by a hand screw 82. The edges of the pressure plate facing the ends of the machine are desirably upturned as at 83 and 84 to permit ready ingress and egress of the jelly rolls with respect thereto.

As the jelly roll, which may now have the designating numeral 58c, passes under the influence of the pressure plate 72, the jelly roll is desirably

rotated on its own axis as well as moved forward bodily by reason of the fact that the pressure plate is stationary while the jelly roll is moving thereunder and in contact therewith on the belt 18. This rotation, which is fairly gentle, is sufficient to set the jelly roll, that is, to give it a good cylindrical form and more or less seal the free edge of the roll to the body of the latter, presenting a good commercial product with sales appeal.

Co-operatively associated with the setting device 71 is provided a cutter knife mechanism indicated generally by the numeral 85 and in this instance comprising a circular knife blade 86 carried by a spindle 87 which is journaled in bearing blocks 88 secured as by fasteners 89 to a pair of pillow-blocks 90 suitably secured to the upper surface of the pressure plate 72. In the vicinity of the circular blade 86 and between the bearings for the blade spindle, the pressure plate is slotted as at 91 to permit the blade to turn therein and have its lower portion depend below the pressure plate centrally thereof into the path of the jelly rolls as at 92, and thereby severing each roll 58c into two similar cylinders or rolls 58d of one-half the length of the original roll.

Rotation of the jelly roll as previously described assists in causing the knife 85 to make a clean quick cut, without the knife touching the conveyor belt.

These two jelly rolls 58d then pass out from under the influence of the pressure plate, carried by the conveyor belt to the end thereof as at 58e and are ready for the wrapping machine. As is well known, the coils or turns of the jelly roll are desirably visible, showing the jelly at the ends of the roll, to enhance its appetizing character.

The invention is of course not intended to be limited to details of structure shown for purposes of exemplification. Furthermore, it is not to be understood that all features of the invention must be used conjointly, since various combinations or sub-combinations may at times be advantageously employed, embodying the invention in one or more of its aspects. Such changes or adaptations may be made as fall within the scope of the appended claims without departing from the invention.

Having described my invention, what is here claimed is:

1. In a jelly roll machine the combination of, an endless belt conveyor to receive a series of cake slabs in abutting edge to edge relation, jelly depositing means suspended over said conveyor including mechanism for effecting discharge of jelly onto the slabs continuously while the conveyor is in motion and the slabs are in abutting relation, another conveyor in end to end adjacent relation with the first mentioned conveyor to receive the slabs successively from the first mentioned conveyor after the jelly is deposited thereon, means for causing the second mentioned conveyor to space the slabs apart, and a flexible apron having one end suspended over the machine at

a place and arranged to be engaged by the slabs after the latter are spaced apart by the said second mentioned conveyor, the other end of said apron being free and dragging on the conveyor and the transverse edges of the slabs being spaced apart by said second mentioned conveyor a sufficient distance to permit the free end of the flexible apron to fall between said transverse edges successively, whereby the leading transverse edge 10 of each slab is picked up by the apron and under the influence of movement of the conveyor the slab is rolled up with the jelly between the convolutions of the roll.

2. In a cake roll machine the combination of, 15 a conveyor to receive a series of cake slabs in abutting edge to edge relation, coating depositing means suspended over said conveyor including mechanism for effecting discharge of coating onto the slabs while the conveyor is in motion and the slabs are in abutting relation, another conveyor in end to end adjacent relation with the first mentioned conveyor to receive the slabs successively from the first mentioned conveyor after the coating is deposited thereon, means for 20 causing the second mentioned conveyor to move faster than the said first mentioned conveyor to space the slabs apart, and roll-up means carried on the machine at a place and arranged to be engaged by the slabs after the latter are spaced apart by the said second mentioned conveyor, 25 the roll-up means including a gravity actuated element and the transverse edges of the slabs being spaced apart by said second mentioned conveyor a sufficient distance to permit the gravity actuated element to fall between said transverse edges successively, whereby the leading transverse edge of each slab is picked up by the roll-up means and under the influence of movement of the conveyor the slab is rolled up with the 30 coating between the convolutions of the roll.

MORRIS COHEN.
